UNITED STATES PATENT OFFICE.

MAREK SEPREC AND STEPHEN SEPREC, OF CLARENCE, PENNSYLVANIA.

LIFE-PRESERVER.

1,116,936.

Specification of Letters Patent. Patented Nov. 10, 1914.

Application filed August 4, 1914. Serial No. 854,983.

To all whom it may concern:

Be it known that we, MAREK SEPREC and STEPHEN SEPREC, subjects of the Emperor of Austria-Hungary, residing at Clarence, in the county of Center and State of Pennsylvania, have invented certain new and useful Improvements in Life-Preservers, of which the following is a specification.

This invention relates to new and useful improvements in life preservers.

The primary object of this invention is to provide a life preserver in the form of an inflatable suit to be worn by the person to prevent drowning, and also to maintain the wearer in a floating position for swimming in the water.

A further object of this invention is the provision of separate inflatable floats secured to the arms, the body, and the legs of the wearer, and being inflatable by a single air inflating pump.

A still further object of this invention is to provide a two-part inflatable suit, having water-tight connections, and provided with a helmet, having a visual opening and a breathing valve,

With these general objects in view, and others that will appear as the nature of the invention is better understood, the same consists in the novel combination and arrangement of parts hereinafter fully described, illustrated in the accompanying drawings, and pointed out in the appended claims.

In the drawings forming a part of this application and in which like-designating characters refer to corresponding parts throughout the several views, Figure 1 is a front elevation of the complete device as worn by a person and having a part broken away and showing a pump connected with the air-inlet pipe. Fig. 2 is a detail enlarged sectional view taken upon line II-II of Fig. 1. Fig. 3 is a transverse sectional view taken upon line III-III of Fig. 1. Fig. 4 is a sectional view taken upon line IV-IV of Fig. 1. Fig. 5 is a sectional view taken upon line V-V of Fig. 1. Fig. 6 is a similar view upon line VI-VI of Fig. 1. Fig. 7 is a sectional view taken upon line VII-VII of Fig. 1, and, Fig. 8 is an enlarged perspective detail view of the cam securing means between the suit sections.

Referring more in detail to the drawings, the device broadly consists in a suit formed of a jacket 10, and trousers 11, each being provided with a means for floating the

wearer of the suit. The trousers 11 are provided with shoes 12 formed therewith so as to constitute a single waterproof garment while the jacket 10 is provided with gloves 13 formed therewith, and making a single garment and with the helmet 14 which is also waterproof, there is formed a complete waterproof covering for the entire upper portion of the body. The jacket 10 is provided with a bottom flange 15 at the waist line of the jacket which has a depending flange 16 adapted for reception within the groove 17 of the belt flange 18 of the trousers. The jacket flange 15 has a dependent bracket 19 secured thereto for pivoting a cam 20 adapted to engage within an outer bottom groove 21 of the belt flange 18.

The wearer of the life-preserver enters the same by putting on the jacket and trousers and tightening the cam 20 for providing a watertight connection therebetween, and in which condition the wearer may enter the water and remain perfectly dry.

The legs of the trousers 11 are provided with outwardly positioned inflatable cushions 22, connected together by means of an air pipe 23, while one of the cushions 22 is connected to one of the inflatable side wings 24 of the jacket 10 by means of the detachable pipe coupling, the details of which are illustrated in Fig. 5.

An air entrance tube 26 is connected to the rear of one of the side wings 24 and adapted to be inflated by means of any form of air pump, such as 27. The two side wings 24 are in communication by means of a connecting pipe 28. The arms 29 of the jacket are each provided with oppositely positioned air cushions 30 the members of each pair being connected together by a tube 31. One cushion of each of the pairs of arm cushions are connected to the adjacent side wing 24 of the jacket by means of a pipe 32. By this arrangement it will be seen that air may be forced through the tube 26 by means of the pump 27 into one of the wings 24, and from whence the air passes to the other wing 24, and from each wing to the pairs of arm cushions, while from the side wing 24 which receives the air from the pump, the air passes to the adjacent cushion 22, and then to the companion cushion 22. It will be seen that all of the cushions are thus inflated by operating the single pump 27 and the air is retained therein by closing the entrance nipple 33. It will be evident the supply pump

may be attached to the entrance nipple 33 of either of the side wings 24, while two of the cam securing means 20 are preferably provided for the suit flanges as illustrated 5 in Fig. 4.

The helmet 14 is provided with a front glass 34 for allowing the wearer to see through the same, while a breathing tube 35 is positioned adjacent the mouth of the 10 wearer, and is secured to the front side of the helmet. The tube 35 is provided with an opening 36 and has a central bore 37 communicating with the interior of the helmet and having a slideable valve 38 mounted 15 therein, while a coil spring 39 which encircles a reduced end portion 40 of the valve holds the latter in a position to normally close the entrance opening 36. When desired to breath through the opening 36, the 20 wearer may pull outwardly upon the valve 38 thus opening the same, while an outward pressure of air upon the valve 38 effects an opening thereof, and allows air to escape from the opening 36.

25 It will thus be seen that the wearer after securing the suit in its proper position and having the several cushions thereof inflated may readily enter the water and float and swim as he desires, and during which time 30 he is able to direct his course and to freely breathe through the helmet valve while at all times he is protected from the water, and is insured against sinking.

35 While the forms of the invention herein fully described are preferred, it is understood that changes may be made in the de-

vice without departing from the scope of the invention as set forth in the claims.

What we claim is:—

1. A device of the class described comprising a jacket and trousers, shoes forming a part of said trousers and gloves and a helmet forming a part of the jacket, a flange upon the bottom of the jacket having a depending annular rib, a belt flange upon the 40 trousers having a groove in the top thereof adapted to receive the said rib, cam locking means between said flanges, inflatable cushions positioned upon the arms, legs, and body portion of the device. 50

2. A life-preserver comprising a jacket, a helmet upon said jacket, an air-breathing valve carried by said helmet, a bottom flange upon said jacket, depending brackets carried by said flange, rocking cams pivoted to said 55 brackets, inflatable cushions carried by the arm portions of said jacket, and inflatable side wings carried by said jacket, and having communication with said arm cushions, a belt flange adapted to engage said bottom 60 flange, and in locked relation with said flange, and float mounting means secured to said belt flange and means for inflating said cushions.

In testimony whereof we affix our signatures in presence of two witnesses.
